FACIAL VAPORIZER

Clifford E. Grube, 8816 Merrill Ave.,
Niles, Ill. 60648

Filed June 5, 1967, Ser. No. 7,373

Term of patent 14 years

(Cl. D83—1)

FIG. 1 is a perspective view of a facial vaporizer, showing my new design;

FIG. 2 is a front view thereof;

FIG. 3 is a side view thereof, the opposite side is a mirror image of the side shown; and

FIG. 4 is a partial rear elevational view thereof, the base portion having the same appearance as the base design shown in FIGS. 2 and 3.

I claim:

The ornamental design for a facial vaporizer, substantially as shown and described.
